CHARLES L. WATKINS, OF RYE, NEW YORK.

WAR GAME.

1,160,348.

Specification of Letters Patent. Patented Nov. 16, 1915.

Application filed April 30, 1915. Serial No. 24,864.

To all whom it may concern:

Be it known that I, CHARLES L. WATKINS, a citizen of the United States, residing at Rye, in the county of Westchester and State of New York, have invented certain new and useful Improvements in War Games, of which the following is a specification.

This invention relates to war games and has for its object to provide an interesting indoor game which will give the players an insight into the military strategy employed in modern warfare.

The apparatus with which the game is played consists of a board and markers or "men", which serve to represent the military units. The board consists of a map showing land, water and other topographical features, and particularly fortifications and important means of communication, such as strategic military railroads. The board is preferably a map of actual country. It is divided into spaces of uniform size, which serve to limit the moves of the various military units. The lines dividing these spaces intersect the military railroads. An advantage of the board thus provided is that it permits of a method of play in which the "men" are allowed longer moves when the move is upon a railroad than when in the open country. This feature is important and instructive, since it forces a player who wishes to be successful to mobilize his "men" along the lines actually employed in the mobilization of troops in modern warfare. In the preferred form the spaces into which the map is divided are in the form of regular hexagons. This method of dividing up the board is advantageous in that it permits the greatest possible freedom of movement to the "men" and thus most closely approximates actual conditions. If the board is divided into squares, each "man" can move in only four possible directions, unless diagonal moves are allowed. The obvious disadvantage of permitting such diagonal moves in a war game is that such moves are necessarily longer than moves to the adjacent squares. If the "men" are thus allowed longer moves in one direction than in another, the effect is to distort the distances upon the map and thus provide a board upon which actual strategic military operations cannot be worked out. When the board is divided into hexagons, each "man" is permitted to move in any one of six possible directions, and the

distance he may move in each one of these directions is the same.

In playing my improved game each player is provided with a plurality of "men", representing military units of various sorts, which are moved upon the map according to definite rules. Each player is permitted to move all his "men" at each play. In this particular my game differs from all other board games with which I am familiar. The feature is important, as it allows each player an opportunity to properly mass his "men" for battle or for transportation and thus introduces features of strategy which cannot be worked out in any game where the player is limited to moving one, or a limited number, of his "men" at each move.

The preferred form of board is illustrated in the accompanying drawing. It consists of a map showing portions of France, Belgium, Switzerland and Germany and all of Luxemburg. The map shows the more important fortified towns and strategic railroads, as well as mountains and rivers. The map is divided into a series of regular hexagons of uniform size. The lines forming these hexagons are preferably of a different color from those representing the topographical features of the map.

The "men" with which the game is played are preferably in the form of lead soldiers, colored differently, to represent the forces of the different combatants. I prefer to provide twenty "men" each for France and Germany, three for Belgium and three for Switzerland, and one for Luxemburg. Five of the twenty "men" of France are of different form from the other fifteen and represent cavalry, while the fifteen remaining represent infantry. The same is true of the "men" of Germany. Each "man" is supposed to represent an army corps of forty thousand men.

The method in which my improved war game is played may best be understood from the rules under which the play takes place. These rules are as follows:

I. *How to start.*—1. France and Germany are the two contenders. The toss of a coin decides which side declares war and gets the first move.

2. All the troops must start from the mobilizing centers, Berlin and Paris, except that one corps may be stationed at each fortified town at the beginning of the game.

II. The object of the game is to capture the enemy's capital or to surround it so that none of the enemy's force can escape.

III. *Moves.*—1. The game is played by moving the men in the hexagonal spaces. Only one man can occupy one space at a time. Moves may be made in any direction.

2. In one turn the player may move all his men once. If he does not care to move some of them, he may leave them where they are, but this does not give him extra moves with the others.

3. Both infantry and cavalry may move three spaces at a time on railroads.

15 4. When not on a railroad, cavalry may move two spaces in one turn.

5. When not on a railroad, infantry may move only one space in one turn.

IV. *Fortified towns.*—1. Each fortified town is surrounded by three shaded spaces, which represent the fort's zone of fire. No enemy can enter one of these spaces unless in sufficient force to capture the town.

2. Fortified towns and their defenders may be captured as follows:

(a) When defended by only one corps—if three hostile corps occupy the three shaded spaces.

(b) When defended by two corps—if six hostile corps occupy six adjacent spaces.

(c) When defended by three corps—if eight hostile corps occupy adjacent spaces—in other words, if they are completely surrounded.

35 3. Not more than three corps can occupy a fortified town for its defense. If a fourth corps occupies a space adjacent to a fortified town already defended by three of its own men, it is liable to capture if the enemy can bring three corps in contact with it.

V. *Open country.*—1. Corps in the open country (*i. e.*, outside of fortified towns or the Harz Mountains) may capture one or more corps of the enemy, if they can be brought in contact with them in sufficient force to outnumber them two to one.

2. When two nearly equal forces are engaged in the open country in a battle line,

any man exposed on the ends, or in advance of his line, may be captured if three corps 50 can be brought in contact with him.

VI. *Neutral countries.*—1. If one side or the other move a man into a space lying wholly within a neutral country, the army of the neutral country is immediately added 55 to the forces of the opponent. In Belgium one corps is quartered at Liege and two at Brussels. In Switzerland one corps is quartered at Basel and two at Zurich. In Luxembourg one corps is quartered at Luxembourg. 60

It is apparent that numerous changes may be made in the game without departing from the spirit of my invention. Thus, some or all of the "men" may represent 65 naval military units instead of only land forces. On the board tangential circles, that is to say, circles inscribed in the hexagons, which I have shown, might be substituted for the hexagons. This would be the 70 full geometrical equivalent of the hexagons and would permit the "men" to move an equal distance in six possible directions.

What I claim is:—

War game apparatus comprising a board 75 bearing a map showing the boundaries of two adjacent belligerent countries and a neutral country adjacent to each of said belligerent countries, fortified towns in each of said countries, each town surrounded by a 80 shaded area indicating its fort's zone of fire, railroads connecting said fortified towns, and a series of equal regular hexagons covering the entire map and having sides which intersect with said railroads; and a plurality of distinguishable sets of "men" representing respectively the military forces of said belligerent countries and said neutral country. 85

In testimony whereof, I have hereunto 90 signed my name in the presence of witnesses.

CHARLES L. WATKINS.
